TRIPOD SUPPORT

Ray S. Lindenmeyer, 2324 Hartzell St., Evanston, Ill.

Filed June 13, 1960, Ser. No. 60,926

Term of patent 14 years

(Cl. D15—2)

FIG. 1 is a perspective view of the tripod support embodying my new design;

FIG. 2 is a top plan view of the tripod support of FIG. 1; and

FIG. 3 is a side elevation view of the tripod support of FIG. 1.

The characteristic features of my new design reside in the portions shown in solid lines in the drawing.

I claim:

The ornamental design for a tripod support, substantially as shown and described.
